SYSTEM FOR WIDE-BAND NEUTRALIZATION
Ben H. Tongue, West Orange, N.J., assignor to Blonder-Tongue Electronics, Newark, N.J., a corporation of New Jersey

Filed Dec. 19, 1960, Ser. No. 76,680

9 Claims. (Cl. 330—78)

The present invention relates to neutralized amplifier systems, and, more particularly, to the wide-band neutralization of single-ended amplifier relay stages and the like.

Numerous types of neutralization circuits have been evolved throughout the years for damping a relay, such as an electron tube or a transistor amplifier or the like, in order to amplify a wide band of frequencies without the deleterious effects of spurious feed-back currents returned from the output to the input circuits of the relay as a result of inherent inter-electrode capacitances and the like. One such proposal is described, for example, in my prior Letters Patent No. 2,761,023, issued August 28, 1956, for Wide-Band Neutralized Radio-Frequency Amplifier.

Systems employing the invention disclosed in this Letters Patent, for example, have been found to work advisably well for neutralizing relatively broad bands of frequencies, such as, for example, either the 54 through 88 megacycle low-frequency VHF television band, or the 174 through 216 megacycle high-frequency VHF television band. If it is desired to effect this neutralization over both the low and high-frequency VHF bands, therefore, one would employ two separate amplifiers; one neutralized, in accordance with the teaching of the said Letters Patent, for the low television band, and the other, for the high television band.

There are occasions, however, where it is desirable to use a single amplifier to embrace a very much wider band, such as a very wide band that is to include both the low VHF television band and the high VHF television band. This requirement would involve wide-band neutralization for frequencies having a ratio of as much as four-to-one; whereas the said Letters Patent involves circuits for neutralizing frequencies of ratios up to about one and six tenths-to-one.

An object of the present invention, accordingly, is to provide a new and improved neutralizing system that can enable the achievement of this very much greater wide-band neutralization, and with the aid of but a single relay stage.

Another approach at neutralization is disclosed in my earlier United States Letters Patent No. 2,778,934, issued January 22, 1957, involving the utilization of an iron-core autotransformer coupled between the input and output of an electron-tube amplifier, for the purpose of neutralizing the feedback between the inter-electrode grid-plate capacitance, but again over a frequency-band ratio of up to about 1.16:1. While such a circuit may be employed, with known techniques, to extend the frequency ratio to somewhat larger ratios, this type of device is not inherently suited, as later explained, to cover bands of the great widths before discussed.

Another object of the invention is to provide a new and improved wide-band neutralization system that may employ in preferred form an autotransformer phase-

2

reversing element in a compensatory output-to-input neutralizing circuit.

An additional object is to provide a novel neutralizing system of more general utility, also.

Other and further objects will be explained hereinafter and will be more particularly pointed out in connection with the appended claims.

The invention will now be described in connection with the accompanying drawing, FIG. 1 of which is a schematic circuit diagram illustrating the invention as applied to a single triode electron tube;

FIG. 2 is also a similar circuit diagram, but illustrating the invention as applied to a transistor relay;

FIG. 3 is a circuit diagram similar to FIG. 2 of a modified transistor version;

FIG. 4 is a graph illustrating the performance characteristics of the present invention, the ordinate plotting current and the abscissa frequency; and

FIG. 5 is a similar circuit diagram of a modified electron-tube circuit.

Referring to FIG. 1, an electron-tube relay amplifier is shown at 1, provided with an anode or plate electrode 3, a control electrode or grid 5, and a thermionic cathode 7. In the output circuit between the plate 3 and the cathode 7, there is connected a load, schematically represented at Z_L , and a source of plate or anode potential, indicated at the amplifier 1, for example, may be a radio-frequency amplifier, in which event, the output load Z_L may assume the form of an output tuned circuit, as is well known in the art. The negative terminal of the plate supply is shown grounded at B^- , and the cathode 7 is connected to the B^- terminal through a by-pass capacitor C_3 and a cathode resistor R_1 .

The term "ground" is used herein to connote not only actual earthing, but, also, other reference potential, such as chassis potential and the like. A grid-leak resistor R_2 is shown connected between the control electrode 5 and the terminal B^- .

Applied to the input circuit, between the control electrode 5 and the cathode 7, is a source of, for example, radio-frequency signals, which may be applied to the terminals 2 and 4; the terminal 2 connecting through a coupling capacitor C_4 to the control electrode 5, and the terminal 4, connecting to the B^- terminal. The stage 40 1 may be followed by subsequent stages, as is schematically represented by the output coupling capacitor C_6 at the upper terminal of the load Z_L .

As is explained in the said Letters Patent, an undesired feedback current normally occurs through the relay 1 between the output circuit and the input circuit by virtue of the inter-electrode capacitance C_{pg} shown dotted between the plate or anode 3, and the control electrode or grid 5. Compensatory network circuits of the said Letters Patent are, therefore, provided between the output and input to produce an out-of-phase compensatory current that mitigates against this undesirable feed-back current and thereby neutralizes the same so that the amplifier 1 may operate over a number of frequencies without interference with the gain of the amplifier.

60 The particular type of compensatory circuit employed herein, is shown comprising, preferably, an autotransformer 9 or other similar phase-reversing network or element, as later discussed. The upper terminal of the autotransformer 9 is connected in the input circuit to the control electrode 5, and the lower terminal is con-

nected by conductor 11 and a series capacitance C_1 to the output circuit plate or anode 3. The performance of this type of compensating device, as explained in the said Letters Patent No. 2,778,934, involves the setting up of a current in the path 11 that is substantially equal and opposite to the feedback current passing from the output to the input through the interelectrode capacitance C_{pg} , whereby the net current between input and output circuits is substantially zero. The autotransformer 9 is preferably, though not essentially, an iron-core bifilar transformer.

In this type of feedback system, as explained in the said Letters Patent 2,778,934, the current fed back along the feedback path C_{pg} , will increase with frequency, as shown by the substantially linear curve A of FIG. 4; indicating increased value of fed-back current of a positive nature, as a function of the frequency of the band of frequencies applied to the relay device 1. The neutralization process involves producing in the compensatory circuit 11, an oppositely-phased or negatively-going current, indicated by the dash-line curve B, which would, at each frequency, have a negative value of current corresponding in value to the positive value of the current in the curve A, thereby completely cancelling out all the feedback current over the frequency range. This method of operation has, however, inherently heretofore been adapted only for relatively limited frequency ranges over which adequate compensatory current can be produced, properly to neutralize the feedback current fed along the path C_{pg} . While those limited frequency ranges seemed relatively wide, as referred to the state of the art at the time the inventions of the said Letters Patent were made, they are narrow compared with the bands available in accordance with the present invention.

Referring to FIG. 4, therefore, curve C represents the type of compensatory current produced in the feedback path 11, comprising the members 9 and C_1 , described in the said Letters Patent. The values represented by curve C, however, except for what may now be called a "narrow" region I (near frequency f_2), closely correspond to curve B and thus do not provide for near-perfect compensation for the actual feed back current at the lower frequencies f_L or the higher frequencies above f_2 , the slope of the curve C rapidly increasing in a negative sense because of the leakage inductance of transformer 9 approaching series resonance with C_1 . The correct value at I is obtained by using a smaller value of C_1 than would produce the initial response of curve B. It is only at the frequency f_2 , or the region slightly above and below the same, that the actual curve C intersects the curve B, as represented by the region I, indicating the correct value $-i_1$ of compensatory current in the feedback circuit 11, substantially equal and opposite to the interelectrode-capacitance-path feedback current $+i_1$. Neutralization is thus achieved at this "narrow" region I, as taught in the said Letters Patent.

It has now been discovered, however, that, through the utilization of an appropriate critical value of capacitance from an intermediate point of the phase-reversing network 9, to a terminal common to both the input and output circuits of the relay 1, and appropriate adjustment of the value of that capacitance together with the series capacitance C_1 in the feedback path 11, entirely new results can be obtained that, for the first time, enable this type of compensatory network, involving the members 9 and C_1 , to be useful over a very wide band of frequencies, far in excess of the bands involved in Letters Patent Nos. 2,778,934 and 2,761,023. In fact, for the first time, a single stage may be readily used, without the deleterious effects of degenerative resistive loading, as in the "neutrode" capacitance bridge neutralization, and neutralized over the complete low- and high-television VHF bands, taken together, including the intermediate FM band, as well; which has not heretofore

been commercially possible with the aid of a single stage.

It remains to explain the details of this discovery that converts an inherently relatively narrow-band frequency neutralizing system (which was previously thought of as "wide-band") into this amazing truly wide-band system. If a very critically valued capacitance C_2 is connected from an intermediate point, shown preferably as the midpoint P of the autotransformer 9 of FIG. 1, to the common terminal B— of the input and output circuits, a response takes place that is vitally different from curve C of FIG. 4. At the lower frequencies f_L , the current in the network circuit 11 of FIG. 1 no longer increases with increasing frequency, as in curve C, but it decreases with increasing frequency over a predetermined region, as shown at the left-hand side D' of dash-dot curve D, FIG. 4. This results in a first low-frequency coincidence with the theoretically desirable curve B at frequency f_1 , and then a subsequent coincidence with the curve B at a high frequency f_3 , providing a very broad intermediate region I', I'', extending over the very broad frequency range f_1 to f_3 , for close approximation to the theoretical curve B.

While in VHF television systems, autotransformers, such as shown at 9, have certainly been by-passed to ground, with capacitors that, at first blush, would appear to correspond to the capacitance C_2 , these prior-art by-pass capacitors have been of the order of 1000 micro-microfarads, more or less, and have only been employed in regions where a bias must be introduced, as described in the said Letters Patent 2,778,934. In accordance with the present invention, on the other hand, a very critical and highly different order of magnitude of value of C_2 , of the order of 80 micro-microfarads, somewhat more or less, in the case of VHF television bands, is employed to perform the very different function of converting the curve C into the curve D by establishing a deliberate series resonance between the portion of the autotransformer 9 disposed between the control electrode 5 and the center or intermediate point P, and the capacitance C_2 , at a low frequency f_L , outside the broad frequency range f_1 to f_3 of interest.

It is usually required, in actual practice, moreover, that the value of the capacitor C_2 and that of the series compensating feedback capacitor C_1 of the path 11 be further adjusted so that the value of the compensatory current near the center of the broadened region I'-I'' (or, substantially intermediate the region from f_1 to f_3) will correspond substantially to the corresponding feedback current $+i_1$ produced within the same region f_1 —to— f_3 , as illustrated in curve A.

By this technique, accordingly, the previously relatively "narrow"-band type of compensatory neutralizing circuit comprising the autotransformer or similar device 9 and the series capacitor C_1 has been startlingly converted from a neutralizing system operable only in the vicinity of a single region I, to a very wide-band neutralizing system operable over a low and high region I'-I'', which, in actual practice, in the case of the said VHF television bands, has been found capable of extending over a 4:1 frequency range—all with a single amplifying tube 1.

From another point of view, this deliberate resonating of the upper portion of the autotransformer 9 above the center tap P with the capacitor C_2 at a frequency below the desired operating range, has the effect, at that low range, of moving the tap P upward, so that the turns ratio of the transformer 9 is effectively altered. A very broad range I'-I'' is produced with the peaked curve D, as contrasted with prior-art ranges in the vicinity of I, as taught in the said prior Letters Patent No. 2,778,934.

A transistor relay 1', analogous to the electron-tube amplifier 1, except that it is provided with a much lower input resistance and is a current-operated device, is shown in FIG. 2 provided with a similar compensating circuit, the corresponding similar parts having similar reference

numerals, and the transistor 1' being shown provided with a base 5', an emitter 7' and a collector 3', and having inherent feedback capacitance through the relay 1', indicated at C_f .

In actual practice, in the system of FIG. 2, there is, in addition to the inherent feedback capacitance C_f , a resistance-containing feedback path. This is indicated in FIG. 3 by the resistance r_{bb} in series with the base 5', and resulting from the so-called spreading resistance of the base. There is thus involved in the feedback capacitance C_f a combination of a capacitance C_{bc} between the collector 3' and an intrinsic internal base 5', and a capacitance C_{be} between the collector 3' and the actual external connection to the base shown as the left-hand terminal of the spreading resistor r_{bb} , the latter being the extrinsic feedback capacitance. In the systems of FIGS. 2 and 3, the appropriate bias for the base is shown obtained by the divider network R_2-R_2' from the negative source $-ve$. The load Z_L is shown connected to the negative terminal of the source $-$, $+$, the positive terminal $+$ of which is shown connected to ground.

In the system of FIG. 3, in order to compensate for this additional resistance-containing feedback path, the capacitor C_2 is shown shunted by a combination of resistance R_4 and capacitance C_4' . The fed-back energy may not be exactly 180 degrees out of phase with respect to the energy fed back from the path C_f , so that the additional compensatory resistance-capacitance network R_4, C_4' may provide for the required correction. There is also not exactly a 90-degree feedback current resulting in the resistance containing path $C_{bc}-r_{bb}$, so that the circuit 11 is provided, in shunt with the capacitance C_1 , with a network R_3, C_3 , such that the compensatory factor of R_3, C_3 keeps the current fed back by the circuit 11 substantially 180-degrees with respect to the feedback through the feedback capacitance C_f .

Attention is further invited to the fact that, inherent in the leads associated with the rather critically valued capacitance C_2 , is a certain amount of inductance. This beneficially serves the purpose of slowing the rate of negative current rise of the right-hand portion of curve D, thereby tending further to widen the range I', I''. This effect may be magnified by adding actual physical inductance L to the capacitor C_2 , as shown in FIG. 5. It must be insured, however, that the added inductance L, while appreciable with respect to the mutual inductance of the autotransformer 9, be not actually comparable or greater than the same. Otherwise stated, the inductance L must not be negligible compared to the mutual inductance of the autotransformer 9; but, on the other hand, it must not be comparable to the same, as otherwise the output of the autotransformer 9 will drop too far at the higher end of the band. The inductance L may be shunted by a capacitance C_6 , FIG. 5, with the combination L— C_6 being operated below its resonance in the region where it appears as an effective inductance, and the overall combination C_2, L, C_6 is capacitive.

Further modifications will also occur to those skilled in the art, and all such are considered to fall within the spirit and scope of the invention, as defined in the appended claims.

What is claimed is:

1. In a wide frequency band amplifier system having relay means provided with input and output circuits sharing a common terminal and in which a feedback current is produced through the relay between the input and output circuits that is to be neutralized by an oppositely phased compensatory current in a neutralizing circuit connected external to the common terminal between the input and output circuits, the neutralizing circuit comprising a phase-reversing impedance element connected in series with first capacitance, whereby the compensatory current is of increasing value as a function of increasing frequency insufficient to neutralize the said feedback current at the lower frequencies of the band, but sufficient

for substantial neutralization at a single narrow region intermediate the band; the improvement of second capacitance connected between an intermediate point of the said impedance element and the common terminal, the second capacitance having a value sufficient to provide a decreasing compensatory current as a function of increasing frequency at the said lower frequencies of value in excess of that required for neutralization in order substantially to widen the said narrow region into a broad region intermediate the band over which sufficient compensatory current for substantial neutralization is achieved, the said first and second capacitance being adjusted to make the value of the compensatory current over the said broad region coincide substantially with the value of the feedback current over the said widened region.

2. A system as claimed in claim 1 and in which the said impedance element comprises an autotransformer.

3. A system as claimed in claim 2 and in which the said second capacitance is connected with inductance of value substantially less than the mutual inductance of the said autotransformer.

4. A system as claimed in claim 3 and in which the said inductance is resonated at a frequency outside the said widened region.

5. A system as claimed in claim 1 and in which at least one of the said first and second capacitances is shunted by a resistance-capacitance network.

6. A system as claimed in claim 1 and in which the said second capacitance is resonated at a frequency outside the said band with the portion of the said impedance element between its said intermediate point and a terminal of the said input circuit other than the said common terminal.

7. A system as claimed in claim 6 and in which the said resonated frequency lies below the said band.

8. In a wide frequency band amplifier system having electron-tube relay means provided with input and output circuits sharing a common terminal and in which a feedback current is produced through the electron-tube relay between the input and output circuits that is to be neutralized by an oppositely phased compensatory current in a neutralizing circuit connected external to the common terminal between the input and output circuits, the neutralizing circuit comprising a phase-reversing impedance element connected in series with first capacitance, whereby the compensatory current is of increasing value as a function of increasing frequency insufficient to neutralize the said feedback current at the lower frequencies of the band, but sufficient for substantial neutralization at a single narrow region intermediate the band; the improvement of second capacitance connected between an intermediate point of the said impedance element and the common terminal, the second capacitance having a value sufficient to provide a decreasing compensatory current as a function of increasing frequency at the said lower frequencies of value in excess of that required for neutralization in order substantially to widen the said narrow region into a broad region intermediate the band over

55 which sufficient compensatory current for substantial neutralization is achieved, the said first and second capacitance being adjusted to make the value of the compensatory current over the said broad region coincide substantially with the value of the feedback current over the said widened region.

9. In a wide frequency band amplifier system having transistor relay means provided with input and output circuits sharing a common terminal and in which a feedback current is produced through the transistor relay between the input and output circuits that is to be neutralized by an oppositely phased compensatory current in a neutralizing circuit connected external to the common terminal between the input and output circuits, the neutralizing circuit comprising a phase-reversing impedance element connected in series with first capacitance, where-

70 75

by the compensatory current is of increasing value as a function of increasing frequency insufficient to neutralize the said feedback current at the lower frequencies of the band, but sufficient for substantial neutralization at a single narrow region intermediate the band; the improvement of second capacitance connected between an intermediate point of the said impedance element and the common terminal, the second capacitance having a value sufficient to provide a decreasing compensatory current as a function of increasing frequency at the said lower

frequencies of value in excess of that required for neutralization in order substantially to widen the said narrow region into a broad region intermediate the band over which sufficient compensatory current for substantial neutralization is achieved, the said first and second capacitance being adjusted to make the value of the compensatory current over the said broad region coincide substantially with the value of the feedback current over the said widened region.
